[57] CLAIM

The ornamental design for a portable radio carrier, as
shown and described.

DESCRIPTION

FIG. 1 is a perspective view of a portable radio carrier
showing my new design;

FIG. 2 is a perspective in extended condition;

FIG. 3 is a left end elevational view with the radio strap
in position of use;

FIG. 4 is a right end elevational view with radio strap in
position of use;

FIG. 5 is a front elevational view of FIG. 3;

FIG. 6 is a top plan view thereof; and,

FIG. 7 is a bottom plan view thereof.
